UNITED STATES PATENT OFFICE.

CHARLES F. HAUNZ, OF BUFFALO, NEW YORK.

DESIGN FOR A CABINET FOR DISPLAYING AND DISPENSING MERCHANDISE.

Application filed December 20, 1926. Serial No. 20,100. Term of patent 14 years.

To all whom it may concern:

Be it known that I, CHARLES F. HAUNZ, a citizen of the United States, residing at Buffalo, in the county of Erie and State of New York, have invented a new, original, and ornamental Design for a Cabinet for Displaying and Dispensing Merchandise, of which the following is a specification, reference being had to the accompanying drawing, forming part thereof, and in which the figure is a perspective view from the rear of the cabinet embodying my new design.

I claim:

The ornamental design for a cabinet for displaying and dispensing merchandise, as shown.

CHARLES F. HAUNZ.
